United States Patent Office.

JOHN R. WILLIAMSON, OF BETHLEHEM, NEW JERSEY.

Letters Patent No. 78,346, dated May 26, 1868.

IMPROVED FRUIT-CAN.

The Schedule referred to in these Letters Patent and making part of the same.

TO ALL WHOM IT MAY CONCERN:

Be it known that I, JOHN R. WILLIAMSON, of Bethlehem, in the county of Hunterdon, and State of New Jersey, have invented a new and improved Fruit-Can; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved fruit-can and cover.

Figure 2 is a similar section of the can alone.

Figure 3 is a plan or top view of the cover and can.

Figure 4 is a detail side view of the cam and lever for holding down the cover.

Similar letters of reference indicate corresponding parts.

This invention relates to a new device for holding down the cover of a fruit-can, and consists of a cam working in grooves in the sides of the can, and provided with a lever, by means of which it can be operated.

The grooves in the sides of the can are or may be semi-annular, or nearly so, so that the cam can be inserted from either side, and applied on either side of the cover.

A, in the drawing, represents a fruit-can, of ordinary or suitable construction, with an oval or other shaped mouth, and with an interior flange or shoulder, *a*, or some other equivalent projection or projections, for the cover *B* to rest upon.

The can is made of glass, stone-ware, or other suitable material, and of suitable size.

The cover is so shaped that it will fit into the mouth of the can and rest upon the flange *a*. The edge of the cover retains an elastic ring, *C*, by means of which an air-tight closure is obtained. The elastic ring is fitted into a V-shaped or other groove formed in the edge of the cover.

On the inside of the can are, on opposite sides, and above the cover *B*, arranged two curved grooves *b b*, as shown in figs. 1 and 2.

These grooves are either semi-annular, as shown, with an enlargement, *e*, in the uppermost part, or they are simply curved like about half those shown.

D is a bar, having a handle, *d*, projecting from it. The bar is as long as the space between the grooved sides of the can, and has at its ends eccentric-gudgeons *e e*, which fit into the grooves *b*.

The bar is inserted by fitting the gudgeons into the upper open ends of the grooves *b*, and by then working them down in the grooves until they reach the lower part of the same. The handle is then bent down upon the cover, whereby the gudgeons are brought above the axis of the bar, and the latter thus serves to hold the cover tight in place, as in fig. 1.

The gudgeons are set slightly toward the handle, that is, their axis is not exactly above, but somewhat in front of the axis of the bar *D*, as indicated in fig. 2, for the purpose of keeping the bar down, and for preventing it from flying up.

The cover may have handles *f f*, to facilitate its removal.

Having described my invention, I claim as new, and desire to secure by Letters Patent—

1. The cam *D*, having the handle *d*, and working in grooves *b*, that are provided in the sides of the can, when said cam is operating, substantially as described, to hold down the cover of a fruit-can, as set forth.

2. The combination of the can *A*, which has the flange *a* and grooves *b*, with the cover *B*, elastic *C*, and cam *D*, all made and operating substantially as herein shown and described.

JOHN R. WILLIAMSON.
